UNITED STATES PATENT OFFICE.

ALDEN B. STARR, OF NEW YORK, N. Y., ASSIGNOR TO STARR PACKAGE MACHINERY COMPANY, INC., A CORPORATION OF MASSACHUSETTS.

COATING-MACHINE.

1,149,154.

Specification of Letters Patent.

Patented Aug. 3, 1915.

Application filed January 30, 1913. Serial No. 745,132.

To all whom it may concern:

Be it known that I, ALDEN B. STARR, a citizen of the United States, residing at the city of New York, in the borough of Manhattan and State of New York, have invented certain new and useful Improvements in Coating-Machines, of which the following is a full, clear, and exact description.

10 This invention relates to the art of coating articles such as receptacles and vessels of various kinds, with paraffin or other material, to render them moisture-proof and liquid-tight. In the manufacture of articles of this kind from paper, pulp and such materials, it is customary to apply to the article after it has received its final shape, a thin coating of paraffin both inside and outside, and in doing this heretofore, difficulty has been experienced in avoiding the waste of paraffin and preventing the application of too much paraffin to the article.

15 The object of my invention is to provide a process and machine by which a thin coating of paraffin or wax can be applied to the external and internal surfaces of the article without waste, and to accomplish this in a rapid and efficient manner.

20 The invention consists in the process and machine hereinafter described in detail and particularly pointed out in the claims.

25 Referring to the accompanying drawing, Figure 1 is a side elevation of my improved machine, a considerable portion thereof being shown in dotted lines; and Fig. 2 is a vertical section on the line A—A of Fig. 1.

30 The supporting frame of the machine is in the form of a table or bench comprising two string-pieces 1, secured together at each end and supported upon legs 2. Depending from the under side of this table is an elongated tank 3 surrounded by a water-jacket 4, the tank being suspended from the string-pieces 1 by means of straps 5. This tank is 35 adapted to contain paraffin or other wax, which is maintained in liquid condition by hot water in the water-jacket, the water being heated by gas flames or any other suitable means applied to the under side of the jacket, but not herein shown. Near one end of the table and also depending from its under side, is a frame 6 supporting an electric or other motor 7, and a pump 8. The pump is adapted to draw the liquid paraffin from 40 the tank 3 through the pipe 9 which is con-

trolled by a valve 10, and to force the paraffin outward through the pipe 11. The motor is adapted to drive a pulley 12 carried by a worm-shaft 13 located above the end of the table; said shaft also having a smaller pulley 14 from which the pump 8 is driven through the belt 14. The worm-shaft 13 drives a worm-gear 15 fixed upon a vertical shaft 16 having at its upper end a beveled pinion 17.

45 Above the table an elongated chamber is provided by a hood 18 of sheet-metal which extends throughout the length of the table, the hood being closed at the top and on both sides. For a portion of its length this chamber is higher than it is in the remaining portion, for a purpose which will herein-after appear. Within the higher portion of the chamber and practically forming the bottom thereof, is an inclined floor 19 which leads from the end of the chamber to the tank 3, to conduct liquid paraffin which may fall upon it into the tank. Throughout the length of the tank, the chamber opens directly thereinto through the space in the table between the string-pieces 1—1, as shown in Fig. 2.

50 In the upper portion of the higher part of the chamber is arranged an endless carrier 20 consisting of two chains running side by side and passing over sprocket-wheels 21 and 22 mounted upon horizontal shafts 23 and 24, this carrier being driven by the pinion 17 in mesh with the bevel gear 25 on shaft 24. The upper run of this carrier is 55 supported by a board or plate 26 extending throughout the length thereof and is prevented from sagging thereby under the weight of the articles which it is to carry. This board is supported by the pieces 27. 60 On the shaft 23 which is located near the point where the higher part of the chamber joins the lower part, is another sprocket-wheel of substantially the same diameter as the wheel 21, over which an endless chain 65 28 passes in a vertical direction to another sprocket-wheel below it on shaft 29. This shaft carries two other sprocket-wheels of the same diameter, and indicated by 30, over which another endless carrier travels, which 70 carrier leads along the full length of the lower part of the chamber and passes over sprocket-wheels 31 mounted upon a suitable shaft at the extreme end or outlet of the machine. This carrier is composed of two 75 110

chains and is of substantially the same construction as the carrier 20, the upper run of which is supported by the stationary board or plate 32 to prevent sagging, this board being sustained by the brackets 33 from the top of the table. These carriers run through the center of the chamber and they are flanked on each side by pipes 34 through which steam or hot water may be passed to 5 keep the chamber at a high temperature and thereby prevent the cooling of the wax. The heating pipes are separated from the middle portion of the chamber by vertical longitudinal partitions 35 and 36 which restrict 10 the central chamber over the carriers to a space but little wider than the distance between the chains comprising the carriers. As the cartons or receptacles such as milk bottles are necessarily of sufficient diameter 15 to permit the same to rest on both chains of the carrier (see Fig. 2), the side walls of the chamber will therefore be in close proximity to the articles supported thereby, which will prevent lateral displacement of 20 such articles when subjected to the flow of paraffin directed against them at different angles, as will be apparent from the operation.

The pipe 11 leading out of the pump 8 is 25 provided with a branch 37, which leads along the top of the table for about half the length of the paraffin tank and is provided at intervals with nozzles 38 which rise through openings in the supporting board 32 and terminate just below the upper run 35 of the carrier supported thereby. The ends of these nozzles may be perforated or wholly open and they may be directed straight upward, as shown, or in various directions, in 40 order to distribute the material thrown by them. The pipe 11 is further provided with branches 39 leading to points below the upper run of the carrier 20 where they are fitted with nozzles 40, which likewise may be 45 of suitable construction to distribute the wax in a generally upward direction. The pipe 11 rises still farther to the top of the higher portion of the chamber and is there fitted with two other nozzles 41 which are 50 directed generally downward toward the carrier but at a sufficient elevation therefrom to permit of the articles to be treated to pass under them without interruption.

Adjacent the sprocket-wheel 21 is attached 55 a transverse rod 42 of a length to extend approximately across the width of the carrier 20. This rod is supported in the extremities of two arms 43 pivoted to the side partitions 35 and 36 upon a screw-stud 44 which passes through a slot in each arm. By 60 this arrangement, the elevation and angular position of the rod may be adjusted with respect to the adjacent axis over which the carrier runs, for a purpose which will hereinafter appear. At the extreme left end 65

and in the roof of the chamber, is a hopper or opening 45, through which the articles are introduced in any suitable manner, one by one, right side up so that they will fall vertically and rest upon the top of the carrier 20.

The operation of the machine is as follows: When the motor is started, the carriers commence to move in a direction to convey the articles from the left toward the right-hand end of the machine, and the pump commences to throw the liquid paraffin into the passageway or chamber through which the articles are conveyed by the carrier. As the articles are passed downward through the opening 45 and deposited upon the carrier, they are immediately moved forward by the carrier so that a bottle upon the carrier will not interfere with one which is being introduced into the chamber. The bottles or vessels of whatever form they may be, rest upon the carrier with their hollow side upward, and as they come within range of the nozzles 40 and 41, they are sprayed, both internally and externally. 85 The nozzles 41, however, are supposed to be of such capacities that they will fill the vessels with the paraffin and thus elevate the center of gravity of the vessels. As the vessels pass over the sprocket-wheel 21, their lower portions are struck and retarded by the cross-rod 42, while the momentum of the vessel, together with the elevated position of its center of gravity, causes the upper part of the bottle to tip over forward, 95 the vessel continuing to turn until its mouth or open end is presented straight downward, when it falls onto the lower carrier and its motion is then continued onward to the rear end of the machine. Of course, when the vessel is thus turned upside down, its contents of liquid paraffin is emptied and falls back into the tank through the open space in the top of the table. Thereafter, the bottle continues to drain until it has passed 100 the rear end of the tank, at which time the surplus paraffin has entirely passed off. During this run upon the lower carrier, the nozzles 38 will be used to apply a second 110 coating of the wax, both inside and outside of the vessel, to insure that the surfaces are entirely covered, but these nozzles need not be used unless they are found necessary, and if not required, they may be cut out by 115 means of the valve 46 in pipe 37.

While I have described my nozzles 41 of such capacities as to fill the vessels with paraffin as they pass under the same, yet it is obvious that by restricting the flow of paraffin through these nozzles, the interior surface of the vessel may be sprayed with paraffin similarly to the method employed in spraying the exterior surface.

This machine has been designed particularly for paraffining paper milk bottles, and 120

is adapted for any size of such a vessel. The quart sizes will easily turn upside down at the point where they are thrown from the upper carrier to the lower, without the aid 5 of the cross-rod 42, but the smaller sizes, especially the half-pints, require the retardation of their lower portions in order to permit the momentum of the upper portion to turn them over. When the smaller sizes of 10 bottles are being treated, a guard 47 may be inserted in the chamber to prevent the bottles from turning over too far; when a bottle reaches its inverted position, the bottom strikes this guard and is prevented 15 from turning further. This guard is not used when the larger bottles are being treated.

My invention obviously is not limited to the particular number or arrangement of 20 nozzles shown in the drawing, since any number may be used both above and below the path of the articles to insure that their surfaces will be fully covered. Likewise, the nozzles may be directed slightly to the 25 right or left as well as straight upward, so as to strike the front and rear of the vessels as they approach and recede from the nozzle.

I am aware of that class of paraffining 30 machines in which the vessels are placed in a carrier and conducted through a tank of paraffin, but so far as known to me, it has never been proposed to spray the vessels with the paraffin as they are moved along 35 upon or by a carrier. One of the difficulties in operating in this manner is to prevent waste of the paraffin. In my machine, the spraying is done in a closed chamber, the walls and surfaces inside of which are 40 heated so that the paraffin that does not actually cling to the surfaces of the vessels undergoing treatment, drains downward and is conducted back to the tank. The paraffin that is collected in the higher por-

tion of the chamber eventually reaches the 45 inclined drain-board and is thereby conducted to the tank, while in the lower part of the chamber, the paraffin, as above mentioned, falls directly into the open top of the tank.

Having described my invention, I claim:—

1. In a coating machine for receptacles and the like, the combination of an elongated chamber, a moving skeleton carrier extending through the same upon which 55 the articles to be coated rest, nozzles located at various points along said chamber arranged to direct the flow of coating material against the interior and exterior surfaces of the receptacles to be coated, the 60 walls of said chamber being in close proximity to the carrier and spaced apart a width to prevent lateral displacement of the receptacles to be coated when subjected to the flow of coating material. 65

2. In a coating machine for receptacles and the like, the combination of an elongated chamber, a moving carrier comprising a plurality of endless belts spaced from each other extending through said 70 chamber and on which the articles to be coated rest, nozzles located along said chamber arranged above and below said carrier to direct the flow of coating material against the interior and exterior surfaces of 75 the receptacle to be coated, the walls of said chamber being in close proximity to the end belts of the carrier, said walls being spaced apart a width to prevent lateral displacement of the receptacles while subjected 80 to the flow of the coating material.

In witness whereof, I subscribe my signature, in the presence of two witnesses.

ALDEN B. STARR.
